CLAIM

The ornamental design for a filter for an industrial dust collector, as shown and described.

DESCRIPTION

1. Filter for an industrial dust collector
- 1.1 : Front perspective view
- 1.2 : Back perspective view
- 1.3 : Front
- 1.4 : Back
- 1.5 : Right
- 1.6 : Left

(Continued)

1.7 : Top

1.8 : Bottom

The filter for an industrial dust collector is embedded within the industrial dust collector and used for collecting and filtering dust produced during machine processing in factories, and discharging the filtered clean air.
